UNITED STATES PATENT OFFICE

132,268

DESIGN FOR A GAME BOARD

Everette A. Wilson and Irven N. Ross,
Salinas, Calif.

Application July 9, 1941, Serial No. 101,997

Term of patent 7 years

To all whom it may concern:

Be it known that we, Everette A. Wilson and Irven N. Ross, citizens of the United States, residing at Salinas, in the county of Monterey and State of California, have invented a new, original, and ornamental Design for a Game Board, of which the following is a specification, reference being had to the accompanying drawing, forming part thereof.

We claim:

The ornamental design for a game board, as shown.

EVERETTE A. WILSON.
IRVEN N. ROSS.
